OIL BURNER

Application filed May 3, 1927. Serial No. 188,457.

This invention relates to an improvement in oil burners and is especially designed for use with ordinary household heating equipment although of course also adapted for 5 general use.

The object of the invention is to provide an oil burner of this character which is of simple and durable construction and which may be readily and easily installed in practically any furnace and which when installed provides for the generation of a high degree of heat while being economical in the consumption of fuel.

A further object of the invention is to 15 provide an oil burner having these advantages and capacities and which is reliable and safe in operation and easy and comparatively inexpensive to manufacture.

Other objects and advantages reside in certain novel features of the construction, arrangement and combination of parts which will be hereinafter more fully described and particularly pointed out in the appended claims, reference being had to the accompanying drawings forming part of this specification and in which

Figure 1 is a perspective view showing one embodiment of the invention.

Figure 2 shows the burner in diametrical 33 vertical section, parts being shown in elevation for the sake of illustration.

Figure 3 is a view in section on line 3—3 of Figure 2.

Figure 4 is a similar view on line 4—4 of 35 Figure 2.

Figure 5 is a detailed perspective view of the combined air deflector and flame spreader.

Referring to the drawings, the numeral 1 40 designates generally a burner constructed in accordance with the present invention. The burner comprises a substantially cylindrical bowl 2 having an outwardly and upwardly flaring flange 3 at its upper end and having an inwardly directed annular bottom plate 4 at its lower end. Intermediate its ends 45 the bowl 2 is provided with an annular supporting ledge 5 which rests on the upper end of a flanged supporting ring 6 carried by a plurality of legs 7.

The burner is placed in the fire box and may be held in position by a filling of sand which is placed in the fire box up to the level of the top of the bowl. The bowl 2 also has integrally formed therewith an inner vertical wall 8 which connects with the bottom wall 4 in spaced relation to the body of the bowl and which terminates at its upper end in the plane of the inner periphery of the flange 3. This wall 8 defines an annular space 9 providing an oil chamber and a wick receiving space.

Oil is supplied to the lower end of this chamber by means of an oil supply pipe 10 which leads from an automatic control box 11 to which oil is supplied from any suitable reservoir. The oil which flows into the space 9 rises under a wick support designated generally at 12 and consisting of a flat annular plate 13 and supporting lugs 14, the plate 13 fitting loosely in chamber 9 and permitting the oil to flow freely around the same. A wick 15 is positioned in the space 9 on the wick support 12 and it consists of eight-ply asbestos cloth which can be burned from either side and which is incased in black iron bands 16. The upper end of the wick terminates just above the upper end of the wall 8.

Means is provided for supplying air to the burner in such manner as to generate a high 80 degree of heat yet make for economy in the consumption of fuel. This means includes an air supply pipe 20 which leads from a blower 21 and which has one end flanged over the margin of an opening in the annular bottom wall 4 as indicated at 22 in Figure 2. A combined air deflector and flame spreader designated generally at 23 is provided and comprises a conical body 25 terminating in an outwardly extending lip 26. The apex of the 85 conical body is disposed adjacent to the end of the pipe 20 which leads into the bowl and the lip 26 overlies the wick 15. The combined air deflector and flame spreader is supported in this position by means of flat ribs or vanes 27 integral with or suitably secured to its periphery at spaced angular intervals and having shoulders 28 which rest on an upstanding flange 29 provided on the bottom wall 4. The 90 vanes 27 are vertically disposed and these 95 28

vanes serve not only to support the combined air deflector and flame spreader in position but also to prevent swirling or vortical movements in the air currents, while constraining them to flow down over and across the upper 5 end of the wick.

In order that the wall of the bowl may be thoroughly heated to preheat and condition the oil for combustion integral radially extending ribs 30 are provided on the flange 3 10 as illustrated to advantage in Figures 2 and 3.

The lower end of the wall 8 and the upstanding flange 29 define an oil pocket or trap 31 between them which serves to collect any 15 oil overflowing the wall 8. The oil collecting in trap 31 flows through pipe 32 to the control box 11 wherein it operates a safety valve.

The combined air deflector and flame spreader 23 is provided with a handle 35 in 20 a recess 36 formed in the upper end thereof so that the combined air deflector and flame spreader may be readily taken from and placed in position on the burner.

In operation the oil flows in through the 25 pipe 10 through the space 9 and thoroughly and evenly saturates the wick 15. The air flows in through the pipe 20 and is constrained by the combined air deflector and flame spreader and its vanes 27 to flow down 30 across and over the upper end of the wick thereby projecting an even and uniform blaze from the burner or around the same and insures complete and thorough combustion of the fuel. In the space 9 and during its passage 35 to the wick 15 the oil is preheated due to the fact that the heat of the flame is taken up to some extent by the ribs 30, flange 3 and body 2 of the bowl.

What I claim is:

40 1. An oil burner comprising a bowl shaped body having an outwardly and upwardly flaring flange at its upper end and provided with a central opening in its bottom, an upstanding flange surrounding said opening, an inner vertical wall extending upwardly from the bottom of said body and spaced laterally from the inner face of the side walls of said body to form a wick receiving chamber, an air supply pipe connected to discharge into 45 said burner through said central opening and a combined air and flame deflector having laterally spaced depending vanes resting on the flange surrounding the central opening of said body to support the deflector and to prevent swirling of the air currents.

50 2. An oil burner comprising a bowl shaped body having an outwardly and upwardly flaring flange at its upper end and provided with a central opening in its bottom, an upstanding flange surrounding said opening, an inner vertical wall extending upwardly from the bottom of said body and spaced laterally from the inner face of the side walls of said body to form a wick receiving chamber, an air 55 supply pipe connected to discharge into said

burner through said central opening and a combined air and flame deflector having laterally spaced depending vanes resting on the flange surrounding the central opening of said body to support the deflector and to prevent swirling of the air currents, said vanes having their edges spaced from the inner wall of the wick chamber providing an air between them and said wall.
